CLAIM

The ornamental design for a control desk for use in
controlling industrial robot.

DESCRIPTION

FIG. 1 is a perspective view of a control desk for use in
controlling an industrial robot showing our new design;
FIG. 2 is a front view thereof;
FIG. 3 is a right-side view thereof;
FIG. 4 is a plan view thereof;
FIG. 5 is a rear view thereof; and
FIG. 6 is a left-side view thereof.
